UNITED STATES PATENT OFFICE

2,535,947

LATCH AND LOCK

Arthur Newell, Minneapolis, Minn.

Application May 2, 1947, Serial No. 745,473

12 Claims. (Cl. 292—5)

This invention relates to improvements in latch and lock mechanisms.

An object of the invention is to provide an improved door latch and lock mechanism.

Another object of the invention is to provide an improved latch and lock mechanism for a door which will be built within the door for securing the same adjacent the central edge of the door and also at points adjacent the top and bottom of said door.

A further object of the invention is to provide an improved form of door knob actuated latching and locking mechanism for a door, said locking and latching mechanisms being disposed respectively at approximately the middle of a front edge of a door and at points on the front edge thereof adjacent the top and bottom.

A still further object of the invention is to provide a door knob operated latch and lock mechanism for a door which will positively project or release a latch and lock mechanism upon the rotation of the door knob in either direction, and a manually operated pivoted locking detent or member for holding and securing said mechanisms in locked position.

Another object of the invention is to provide an improved door latch and lock mechanism which will be highly efficient in operation, and relatively inexpensive to manufacture and produce.

Other objects will appear as the description proceeds.

In the accompanying drawings which form a part of this application,

Figure 1 is a vertical sectional view through the adjacent portions of a door and jamb being broken away to show the relative position of the lock and latch mechanisms found within the same;

Figure 2 is a view taken on the line 2—2 of Figure 1;

Figure 3 is a front elevation of the lock plate supported upon the edge of the door jamb;

Figure 4 is a front elevation of one of the latch plates supported upon the lower and upper edge of the door jamb;

Figure 5 is a side elevation of the lock and latch actuating casing or housing showing its position within a door which is shown in section;

Figure 6 is a front edge view of a portion of a door showing the lock and latch housing and door-knob in operative position therein;

Figure 7 is a sectional view taken on the line 7—7 of Figure 6, and;

Figure 8 is a sectional view taken on the line 8—8 of Figure 5.

Like characters of reference are used throughout the following specification and the accompanying drawings to designate corresponding parts.

In carrying out the invention, there is provided a door generally designated by the reference numeral 1, and a cooperating door jamb generally designated by the reference numeral 2.

The edge 3 of the door 1 will be formed with vertically extending elongated recesses 4 and 5 adjacent its top and bottom, and will be formed with an enlarged centrally disposed recess 6 for receiving the housing 7 in which the lock and latch operating mechanisms hereinafter described will be housed.

Spaced vertically disposed aligned grooves 8 and 9 will be formed in the edge 3 of the door 1, and will connect the recesses 4 and 5 with the enlarged centrally disposed recess 6.

Face plates 10 and 11 having circular apertures 12 and 13 formed therethrough will be secured to the edge 3 of the door 1 to overlie the elongated latch receiving recesses 4 and 5, and will be secured in place by the screws 14 and 15 respectively.

The edge 16 of the door jamb 2 will also be recessed as at 17 and 18 opposite the recesses 4 and 5, and will be closed by the face plates 19 and 20 respectively, being held in place by means of the screws 21 and 22. Circular openings 23 and 24 will be formed through the face plates 19 and 20 to receive portions of the ball latches 25 and 26 supported in the elongated recesses 4 and 5 in said door 1.

The metal liner members 27 and 28 will be disposed within the elongated recesses 4 and 5, and will be formed with the angled bearing surfaces 29 and 30 upon which the ball latches 25 and 26 will roll when being projected to extend through the openings 12 and 13 in the face plates 10 and 11, and through the openings 23 and 24 in the face plates 19 and 20 overlying the recesses 17 and 18 in the door jamb 2.

Follower heads 31 and 32 having angled bearing surfaces 33 and 34 respectively will be slidably disposed within the linear members 27 and 28, with said surfaces 33 and 34 being adapted to engage the ball latches 25 and 26 for operating and projecting the same when said follower heads 31 and 32 are moved respectively upwardly and downwardly by means of the actuating rods or wires 35 and 36 attached thereto by their bent ends 37 and 38, said actuating rods or wires 35 and 36 flying within said grooves or channels 8 and 9 formed in the forward edge 3 of the door.

Coil springs 39 and 40 will be disposed about the rods or wires 35 and 36 inwardly of the ends of the follower heads 31 and 32 for normally urging the same to their outer or projected position for operating the ball latches 25 and 26.

The housing 7 in which the lock and latch operating mechanism is housed includes the spaced parallel extending side plates 41 and 42 secured to the face plate 43 which is attached

to the edge 3 of the door 1 by means of the screws 44.

A spindle 45, which is approximately square or rectangular in cross section, extends transversely of the side plates 41 and 42 and through the door 1, supporting the door knobs 46 and 47 upon the opposite ends thereof, while escutcheon plates or disks 48 and 49 are disposed about the spindle 45 between the outer surface of the door 1 and said door knobs 46 and 47, furnishing the trim for the said door knobs.

A pair of upper and lower locking bars or fingers 50 and 51 are pivotally supported for vertical movement upon the pivot pins 52 and 53 between the side plates 41 and 42 adjacent their inner ends which are arcuately curved as at 54 and 55 towards each other at their inner ends, while their outer ends project through the vertically aligned openings 56 and 57 formed through the face plate 43 of the housing 7. The inner ends of the rods or wires 35 and 36 are pivotally attached to the forward ends of the locking bars or fingers 50 and 51 whereby when said fingers 50 and 51 are spread apart, the ball latches 25 and 26 will be simultaneously projected into latched position, and when said fingers 50 and 51 are moved towards each other, the ball latches 25 and 26 will be retracted to their unlatched position.

The inner edges of the fingers 50 and 51 will be notched out as at 58 and 59, and will cooperate with the rockable finger operating cam 60, which in turn is actuated by the cam actuating member 61 secured upon the square spindle 45, whereby rotation of said spindle 45 in either direction will cause the member 61 to engage and operate the finger operating cam 60 to move the arcuate inner ends 54 and 55 of the locking fingers 50 and 51 outwardly, thereby moving the outer ends of said fingers 50 and 51 inwardly to unlocked position.

A locking face plate 62 having opposed locking notches 63 and 64 formed therein, is provided with sloping opposed surfaces 65 and 66, said face plate 62 being secured over a recess 67 in the edge 16 of the door jam 2, being held in fixed position by means of the screws 68.

A key hole 69 is formed through the plates 41 and 42 of the lock housing 7, whereby the forked ends 69' of the locking detent 70 which is pivoted upon the pin 71 and fastened by the spring 72 disposed about pin 71, will project the hooked end 73 of said detent 70 about a pin 74 disposed transversely of the slot 75 formed in the lower locking finger 51, for holding the fingers 50 and 51 in locked position when engaged or seated in the locking notches 63 and 64 in said locking face plate 62 attached to the edge 16 of the door jam 2.

A stop spur 76 will be struck from the side plate 41 and pushed inwardly, serving to limit the rotary movement of the cam actuating member 61 for preventing full rotation of the same. The springs 39 and 40 disposed about the rods or wires 35 and 36 next to the follower heads 31 and 32 will cause the locking fingers 50 and 51 to which they are attached, to be normally and resiliently moved into locked position.

From the foregoing description, it will be apparent that there has been devised and provided a highly efficient form of door latch and lock mechanism which will be automatically operated by rotation of the door knobs in either direction, and which may be secured in locked position by means of any suitable key placed within the key hole 69 provided therefor and brought into engagement with the feet 69' in the locking detent 75

10 which will then be rotated to overlie the pin 74, thus holding said latch and lock mechanism secure.

While the preferred embodiment of the instant invention has been illustrated and described, it will be understood that it is not intended to limit the scope of the invention thereto, as many minor changes in detail of construction may be resorted to without departure from the spirit of the invention.

Having described the invention, what is claimed as new is:

1. In combination with a door and latch and lock mechanisms therefor including a lock mechanism housed in the edge of said door midway of its length, latch mechanisms housed in the edge of said door above and below said lock mechanism, a spindle for said lock mechanism, door knobs on the ends of said spindle, pivoted locking fingers adjacent said spindle having resiliently tensioned means connected with said latch mechanisms, an operating cam engageable with said locking fingers, and means supported by said spindle engageable with said operating cam for simultaneously operating said lock and latch mechanisms.

2. In combination with a door and frame jamb therefor, of latch and lock mechanisms disposed in the edge of said door in spaced relation, a spindle for said lock mechanism, door knobs on the opposite ends thereof, pivoted locking fingers in said lock mechanism, ball latches for said latch mechanism, follower heads for projecting said ball latches and operating rods between said locking fingers and said follower heads whereby the same will be simultaneously operated upon the rotation of said spindle in either direction.

3. In combination with a door and frame jamb therefor, of a latch and lock mechanisms therefor disposed in the edge of said door in spaced relation, a spindle for said lock mechanism, door knobs on the opposite ends thereof, pivoted locking fingers in said lock mechanism, ball latches for said latch mechanism, follower heads for projecting said ball latches and operating rods between said locking fingers and said follower heads whereby the same will be simultaneously operated upon the rotation of said spindle in either direction, said locking fingers and ball latches being adapted to engage apertured keeper plates.

4. In combination with a door and latch and lock mechanisms therefor including a lock mechanism housed in the edge of said door midway of its length, latch mechanisms housed in the edge of said door above and below said lock mechanism, a spindle for said lock mechanism, door knobs on the ends of said spindle, pivoted locking fingers including an arcuately curved portion adjacent said spindle having resiliently tensioned means connected with said latch mechanisms, an operating cam rideable on the inner arcuate surface of said lock fingers, and a second cam supported by said spindle engageable with said operating cam for simultaneously operating said lock and latch mechanisms.

5. In combination with a door and frame jamb therefor, of latch and lock mechanisms disposed in the edge of said door in spaced relation, a spindle for said lock mechanism, door knobs on the opposite ends thereof, pivoted locking fingers in said lock mechanism, ball latches for said latch mechanism, metal liners in said latch mechanisms, tensioned follower heads for projecting said ball latches and operating rods 75 between said locking fingers and said follower

heads whereby the same will be simultaneously operated upon the rotation of said spindle in either direction.

6. The combination of claim 5 wherein said liners and follower heads form angled bearing surfaces seating the ball latches therein.

7. The combination of claim 6 wherein said tension means are coil springs between said liners and follower heads and said rods terminate in said follower heads for actuating them into latching or unlatching position.

8. In combination with a door and frame jamb therefor, a lock housing in said door, said lock housing including side plates and an apertured face plate, a spindle extending through said housing, pivoted latching fingers secured in said housing extending through said apertured face plate and adapted to engage with a keeper, means actuated by said spindle pivoting said fingers into operation, latch means mounted in spaced relation on said door, operating rods connecting said pivoted latch fingers and said latch means, and door knobs on the end of said spindle actuating said fingers to open and close the door.

9. In combination with a door and frame jamb therefor, a lock housing in said door, said lock housing including side plates and an apertured face plate, a spindle extending through said housing, pivoted latching fingers secured in said housing extending through said apertured face plate and adapted to engage with a keeper, an operating cam engageable with said fingers, means supported by said spindle engageable with said operating cam, latch means mounted in spaced relation on said door, operating rods connecting said pivoted latch fingers and said latch means, and door knobs on the end of said spindle

actuating said fingers to open and close the door.

10. In combination with a door and frame jamb therefor, a lock housing in said door, a spindle extending through said housing, pivoted latching fingers secured in said housing, an operating cam engageable with said fingers, means supported by said spindle engageable with said operating cam, latch mechanisms including ball latches and follower heads projecting said ball latches, operating rods connecting said pivoted latch fingers and said follower heads, and door knobs on the end of said spindle actuating said fingers to open and close the door.

11. The combination of claim 10 wherein said latch mechanisms includes liners and tension means retained between said liners and follower heads urging said ball latches into latching position, said liners and follower heads having angled bearing surfaces seating the ball latches therein.

12. The combination of claim 10 wherein said operating rods are secured in said follower heads and extend into said locking fingers to operate said ball latches when said fingers are pivoted.

ARTHUR NEWELL.
